UNITED STATES PATENT OFFICE.

WILLIAM M. BOENNING, OF MANITOWOC, WISCONSIN, ASSIGNOR TO ALEC J. GERARD, OF CHICAGO, ILLINOIS.

PORTABLE WIRE-TYING MACHINE.

1,391,820.

Specification of Letters Patent. Patented Sept. 27, 1921.

Continuation of application Serial No. 250,685, filed August 20, 1918. This application filed June 5, 1920. Serial No. 386,692.

To all whom it may concern:

Be it known that I, WILLIAM M. BOENNING, a citizen of the United States, residing at Manitowoc, in the county of Manitowoc and State of Wisconsin, have invented certain new and useful Improvements in Portable Wire-Tying Machines; and I do hereby declare the following to be a full, clear, and exact description of the invention, 10 such as will enable others skilled in the art to which it appertains to make and use the same.

This invention relates to wire tying machines, and has for its object to provide a 15 mechanism which will be comparatively inexpensive to manufacture and more efficient in action than those heretofore proposed.

With these and other objects in view the invention consists in the novel details of construction and combinations of parts more fully hereinafter disclosed and particularly pointed out in the claims.

This case is a continuation of my copending application #250685, filed August 20, 25 1918, and entitled Wire tying machine.

Referring to the accompanying drawings forming a part of this specification in which like numerals designate like parts in all the views:—

30 Figure 1 is a diagrammatic plan view of a machine made in accordance with this invention;

Fig 2 is a side elevational view of the parts shown in Fig. 1;

35 Fig. 3 is a view taken on the line 3—3 of Fig. 4;

Fig. 4 is a view taken on the line 4—4 of Fig. 2, looking in the direction of the arrows; and

40 Fig. 5 illustrates the twisted knot made by this invention.

1 indicates one section of the metal frame work, 2 the other section thereof, and 3 and 4, flanged members rigid with said sections 45 by which the latter are secured together as by the bolts 5. The section 1 has the upturned lugs or members 6 and 7 through which pass the main operating shaft 8, and which shaft also has a bearing in the flanges 3 and 4 as shown. Said flanged members 3 and 4 are hollowed out to accommodate the driving pinion 9 having the hub 10 journaled in said members 3 and 4, and rigid with the shaft 8. Said pinion 9 meshes with

the wire twisting pinion 11 provided with 55 the hub 12, also journaled in said members 3 and 4. Said hub 12 has the hollowed out slotted spaces 13 and 14 on each side of the pinion 11, and the latter is provided with the wire twisting slot 15, as will be more fully 60 disclosed hereinafter. As will be clear from Figs. 2, 3 and 4, the flanged members 3 and 4 are respectively provided with the slots 16 and 17 which extend outwardly beyond the slotted pinion 11 and which are wider 65 than is the slot 15 for a purpose that will presently appear.

The section 2 of the frame work is provided with the boss 18 which is slotted as 70 at 19 to receive the wire and the upper portion of which is threaded to receive the clamping screw 20 provided with the hand actuated means 21, as shown. The lower end 22 of said screw 20 is flat and of such dimensions as will clamp only one strand of the 75 wire, as will be clear from Figs. 1, 2 and 3. Said section 2 is also provided with a rear extension 24, having a flat under surface 25, which serves as a means to steady the machine during the twisting operation, as 80 will presently appear. Near the slot 19 in the boss 18, said section 2 is provided with the pins or posts 26, which are separated by a distance substantially equal to the diameter of the wire to be used in the machine, and 85 the section 1 is provided with a boss or an enlargement 28 having two posts 29 similar to the posts 26 and likewise separated by a distance slightly greater than the diameter of the wire to be twisted. Said enlargement 90 28 is rigid with the lug 7 which terminates in the upright boss 30 in which is journaled for rotation the slotted wire tensioning member 31, having the operating handle 32. Said frame section 1 is also provided with 95 the flat under surface 33 forming a continuation of the surface 25 of the frame section 2. The shaft 8 is provided with the operating handle 34, the hub 35 of which carries the index marking 36 adapted to 100 register with the index or mark 37 on the lug or journal 6.

The operation of this improved wire tying machine will be clear from the foregoing but may be briefly summarized as follows. The operator clamps one end 40 of the wire in the slot 19 by screwing down on the end 22 of the screw 20, whereupon he

- passes the bight 41 between the posts 26, into the slots 17, 15 and 16, between the posts 29, behind the tensioning member 31, over the top 42 of the box 43, down the side, under the bottom, and up the other side back to the slot between the posts 29, whereupon the bight 44 of the wire also passes into the slots 17, 15 and 16, between the posts 29, and into the slot 45 of the tensioning post 31. The box being thus encircled by the wire 46, the handle 32 is operated to turn said post 31 and thus wind up the bight 44 thereon. This winding operation tensions the wire to any degree desired, whereupon, while the wire is still under tension, the handle 34 is operated to turn the shaft 8, the gear pinion 9 and the slotted gear pinion 11. The bights 41 and 44 being held against rotation by the slots between the posts 26 and 29, the slots 17 and 16, and the hollow spaces 13 and 14 in the hub 12 being of sufficient dimensions to permit a free rotation of said bights, while the slot 15 like those between said posts being too narrow for such rotation, it results that a turning of the pinion 11 in the manner described will twist together said bights 41 and 44 while under tension, and into the knot shown in Fig. 5.
- After the twisting operation, the tensioning post being vertically slidable in the boss 30, said post is raised until the wire wound therearound during the tensioning operation, strikes the underside 50 of said boss 30, whereupon said wire is forced off said post 13. At the same time, the end 40 is released from the clamping screw 20, and then the entire machine may be slid out from under said wire.
- An important feature of the invention resides in the construction by which the two sections of the frame 1 and 2 have smooth bottoms 33 and 25, which lie flat down upon the top 42 of the box, so that the bights 41 and 44 of the wire likewise lie comparatively close to the top of the box, and in fact are only spaced therefrom by a distance equal to one-half the diameter of the pinion 11.
- In addition to this, the surfaces 25 and 33, being continuations of each other, and the frame work being comparatively light, it is an easy matter for the operator to hold the entire machine firmly in contact with the box 43 while performing the twisting operation, and thus he insures a much better job than would otherwise be the case.
- Another important feature of the invention resides in the fact that the section 1 extends a considerable distance along the top of the box away from the twisting gears or pinions 9 and 11, so that the handle 34 may be located beyond the extreme edge of the box and thus may be operated along down opposite the vertical side of the box

without coming in contact with the top thereof. This enables the machine to be made of a lighter construction than would be otherwise the case.

Another important feature of the invention resides in the fact that the extension 24 is disposed in a position at a considerable angle to the section 1 of the frame work, and it extends a considerable distance from the twisting slot 15 so that while the levers 34 and 32 are being operated, said extension 24 acts as a means to prevent the machine from tipping. In other words, a comparatively slight pressure by the hand upon the extension 24 holds the machine firmly in position during the operation thereof.

It will now be clear that by providing the ribs on the frame work as shown, the latter may be made of a minimum lightness, and by disposing of the parts as disclosed, it may be made of a maximum efficiency to the end that the bights of the wire may be readily and rapidly twisted together and the machine disengaged from the finished tie in a minimum of time.

By providing the indices 36 and 37, the operator may turn the handle 34 any desired number of times, and thus put into the bights 41 and 44 any desired number of turns, and yet be sure, at the end of the twisting operation, that the slots 15, 16 and 17 will all be in register. It is obvious that unless said slots are stopped in register with each other that it would not be an easy matter to get the wire out of the twisting mechanism at the end of the tying operation.

It is obvious that those skilled in the art may vary the details of construction, as well as the arrangements of parts without departing from the spirit of the invention, and therefore I do not wish to be limited to the above disclosure except as may be required by the claims.

What I claim is:—

1. In a wire tying machine, the combination of a frame having a flat surfaced bottom adapted to contact with the top of the box to be wired; an extension of said frame adapted to overlie the edge of said box and provided with an operating handle; a second extension of said frame disposed at an angle to said first named extension and adapted to aid in steadyng the machine during the wire twisting operation; means for putting the wire under tension; and means operated by said handle adapted to twist together two bights of said wire while under tension, substantially as described.

2. In a wire tying machine, the combination of a frame having a flat surfaced bottom adapted to contact with the top of the box to be wired; an extension of said frame adapted to overlie the edge of said box and provided with an operating handle; a second extension of said frame disposed at an

- angle to said first named extension and adapted to aid in steadyng the machine during the wire twisting operation; means for putting the wire under tension comprising a handle and a rotatable slotted post; and means operated by said first named handle adapted to twist together two bights of said wire while under tension, substantially as described.
- 10 3. In a wire tying machine, the combination of a frame having a flat surfaced bottom adapted to contact with the top of the box to be wired; an extension of said frame adapted to overlie the edge of said box and provided with an operating handle; a second extension of said frame disposed at an angle to said first named extension and adapted to aid in steadyng the machine during the wire twisting operation; means for putting the wire under tension; and means operated by said handle comprising a shaft, a driving gear rigid with said shaft and a slotted gear operated by said driving gear adapted to twist together two bights of said wire while under tension, substantially as described.
- 15 4. In a portable wire tying machine, the combination of a frame having a flat bottom adapted to rest on and to slide over the top of a box; a wire twisting means mounted in said frame; a wire tensioning means mounted in said frame; and an extension of said frame having a flat bottom also adapted to rest on the top of the box and to aid in steadyng the machine during the wire twisting and wire tensioning operations, substantially as described.
- 20 5. In a wire tying machine, the combination of a frame having a flat bottom adapted to rest on the top of a box; a wire twisting means mounted in said frame comprising a driving pinion and a slotted pinion; a wire tensioning means comprising a slotted rotatable tensioning post mounted in said frame; and an extension of said frame having a flat bottom also adapted to rest on the top of the box and to aid in steadyng the machine during the wire twisting and wire tensioning operations, substantially as described.
- 25 6. In a wire tying machine, the combination of a frame having a flat bottom adapted to rest on the top of a box; a wire twisting means mounted in said frame comprising a slotted pinion and a pair of separated wire holding posts on each side of said pinion; a wire tensioning means mounted in said frame; and an extension of said frame having a flat bottom also adapted to rest on the top of the box and to aid in steadyng the machine during the wire twisting and wire tensioning operations, substantially as described.
- 30 7. In a wire tying machine, the combination of a frame having a flat bottom adapted to rest on the top of a box; means to clamp one end of the wire; a wire twisting means mounted in said frame comprising a slotted wire twisting pinion and a pair of wire holding posts on each side of said pinion; a wire tensioning means mounted on said frame; and an extension of said frame having a flat bottom also adapted to rest on the top of the box and to aid in steadyng the machine during the wire twisting and wire tensioning operations, substantially as described.
- 35 8. In a portable wire tying machine, the combination of a frame made in two parts and having a flat bottom; a wire twisting means mounted between said parts; means for clamping one end of the wire mounted on one of said parts; means for tensioning the wire mounted on the other of said parts; an extension adapted to overlie the edge of the box being wired; an operating handle for said twisting means carried by said extension; and a second extension disposed at an angle to said first named extension to aid in steadyng the machine during the twisting and tensioning operations, substantially as described.
- 40 9. In a portable wire tying machine, the combination of a frame made in two parts and having a flat bottom; a wire twisting means mounted between said parts and comprising a slotted pinion having a slotted hollowed out hub; means for clamping one end of the wire mounted on one of said parts; means comprising a slotted rotatable and vertically movable post for tensioning the wire mounted on the other of said parts; an extension adapted to overlie the edge of the box being wired; an operating handle for said twisting means carried by said extension; and a second extension disposed at an angle to said first named extension to aid in steadyng the machine during the twisting and tensioning operations, substantially as described.
- 45 10. In a portable wire tying machine, the combination of a frame having a smooth flat bottom adapted to rest on the surface of the package to be wired; wire tensioning means comprising a vertically disposed slotted member carried by said frame; means also carried by said frame for twisting together two bights of the wire while under tension, and an extension of said frame adapted to aid in steadyng the machine during the twisting operation, substantially as described.
- 50 11. In a portable wire tying machine, the combination of a frame having a smooth flat bottom adapted to rest on and slide over the surface of the package to be wired; wire tensioning means carried by said frame; means also carried by said frame for twisting together two bights of the wire while under tension; and an extension of said frame

- frame to aid in steadyng the machine during the twisting operation, substantially as described.
12. In a portable wire tying machine, the combination of a frame having a smooth flat bottom adapted to rest on the surface of the package to be wired; means to hold one end of the wire; vertically movable wire tensioning means carried by said frame adapted to facilitate the removal of the wire after the twisting operation; and means also carried by said frame for twisting together two bights of the wire while under tension, substantially as described.
13. In a portable wire tying machine, the combination of a frame having a smooth bottom adapted to slide over the surface of the package to tighten one bight of the wire during the twisting operation; clamping means for causing the end of said bight to move with the machine; means for holding parallel disposed bights of the wire in a predetermined position in said frame during said twisting operation and preventing portions of said bights from rotating during the twisting operation; and means comprising a slotted pinion for twisting said bights together, substantially as described.
14. In a portable wire tying machine, the combination of a frame having a smooth bottom adapted to slide over the surface of the package to tighten one bight of the wire during the twisting operation; means for holding each end of the wire before the twisting operation; means for holding parallel disposed bights of the wire in a predetermined position in said frame during said twisting operation, and preventing portions of said bights from rotating during the twisting operation; and means comprising a slotted pinion for twisting said bights together, substantially as described.
15. In a portable wire tying machine the combination of a frame having a smooth bottom adapted to slide over the package during the twisting operation; means for securing one end of the wire to be tied; means for twisting two parallel disposed bights of said wire together; means to prevent said bights from rotating during the twisting operation; and means for exerting a tension on said wire before the twisting operation, substantially as described.

In testimony whereof I affix my signature.

WILLIAM M. BOENNING.
